UNITED STATES PATENT OFFICE

GEORG JOACHIM KARL BEHRMANN, OF RIJSWIJK, NETHERLANDS, ASSIGNOR TO NAAMLOOZE VENNOOTSCHAP INGENIEURS KANTOOR VOOR SCHEEPSBOUW, OF THE HAGUE, NETHERLANDS

SUBMARINE BOAT

Application filed November 21, 1928, Serial No. 320,969, and in Germany November 22, 1927.

The application to Diesel-motors of loading-compressors, which are driven on by turbines impelled by the exhaust gases, has got recently more and more in vogue, but in sub-
5 marine boats the arrangement of the aggre-
gates is very difficult owing partly to the use
to nearly the full hold of said ships and
partly to the strong radiating heat of the tur-
bines.

10 The object of the invention is to clear away
said difficulties by arranging the turbine and
the compressor entirely or partially outside
the shell of the boat, but by so doing atten-
tion must be paid to several requirements.

15 It is first of all necessary to introduce the
exhaust gases in a hot state into the turbine,
hence the usual cooling of the exhaust pipe
inboard is no longer admissible. Besides it
is of importance to make the pipes as short
20 as possible. Further, a strong transmission
of heat to the wall of the ship should be
thoroughly prevented. Moreover the hot tur-
bine cannot support, at least not in the struc-
tures known hitherto, the quick cooling when
25 the boat plunges, in case the turbine is ar-
ranged unsheltered outboard and has been
operating until just before the plunge. If
the latter is wanted a cover is required, being
able to resist pressure and which can be shut
30 off against the outer water and is cooled by
water, according to what has been stated
above, there where it penetrates the body of
the boat.

With a structure, however, which meets the
35 requirements with respect to the resistance
against pressure and especially to the stuffing,
a free arrangement outboard is admissible, if
care be taken that by means of proper stop
cocks the turbine may be put out of operation
40 in good time before the plunge.

The space of time between the putting out
of operation and the plunge can be shortened
by lowering the temperature of the turbine
more promptly than by the radiating of heat
45 by means of water e. g. by sprinkling. The
possibilities of the realization of the afore-
said idea are by way of example represented
in the Figures 1-8 inclusively of the accom-
panying drawings.

50 First of all the form represented in Figures

1 and 2 will be described, in which Fig. 1 is a
section on the line I—I of Fig. 2. In this
form the turbine A and the compressor C,
impelled by said turbine, are arranged in a
box B which is able to resist pressure. 55

The exhaust pipe D of the Diesel motor
E (see Fig. 2) is connected with the box B.
The exhaust gases arrive by means of this
conduit into the turbine and leave the same
through the stuffing box F, with which a pipe
is connected which is not shown and which
60 opens in the atmosphere. By means of the
conduit G atmospheric air is sucked by the
compressor C and through the conduit H the
air which is compressed in the compressor
is introduced as the loading air into the Diesel
65 motor. In this form the box B is arranged
in the cover of an outer tank J and this re-
quires the penetration of the shell K of the
submarine boat by the exhaust pipe D of the
70 Diesel motor and of the air conduit H.

If this is to be avoided the box B may,
as is shown in Fig. 3 be partly entered into
the body K of the submarine boat. The con-
necting pipes D and H of the Diesel motor E 75
may then be arranged inboard.

Figs. 4 and 5 (the latter being a side view)
show the arrangement of the turbine A with
the compressor C in the superstructure L of
the boat. In this form the complete aggre-
gation (turbine and compressor) is, in oppo-
sition with the foregoing form, not arranged in
the box B but only the compressor C thereof,
because the compressor is able to support a
sudden cooling when the boat plunges and
85 the turbine cannot. Moreover Fig. 5 shows
in which manner by closing the stop cocks N O
P Q and opening the stock cock R the turbine
may be put out of operation. The exhaust
gases of the turbine then arrive in the atmos-
phere through the conduit S. 90

If it is desirable to relinquish a covering
being able to resist pressure likewise of the
turbine, Fig. 6, which is a variant of the
side view in Fig. 5, shows the measures which
95 may be taken to render said cover superfluous.
By means of the arrangements of the
stop-cocks, described in connection with Fig.
5, some time before the intended plunge, the
exhaust gases of the turbine are carried 100

through the conduit S and the stuffing box into the atmosphere. At the same time the turbine is sprinkled with cooling water by means of a cooling hose T which is provided with apertures, the turbine being to this end provided with a revetment U which is not able to resist pressure. The turbine is then cooled slowly and the plunge will not be prejudicial. If the cooling arrangement is to be omitted, the operation of the turbine should be stopped much sooner so that the same is cooled naturally by the surrounding atmosphere and when plunging it may be considered sufficiently cooled.

15 Fig. 7 and the side view in Fig. 8 show an arrangement of the compressor C inboard next to the Diesel motor E, whilst the turbine A, which is cooled by the atmosphere, is placed outboard. This arrangement is chosen if it is desirable to protect the staff of the boat against the transmission of heat and if for the avoidance of long air ways it be better to place the compressor near by the Diesel motor.

20 25 What I claim is:—

1. In a submarine boat, turbines, impelled by the exhaust gases of Diesel motors, and compressors, both the turbines and compressors being arranged outboard.
2. In a submarine boat, turbines, impelled by the exhaust gases of Diesel motors, and compressors, both the turbines and compressors being arranged outboard and being surrounded jointly or separately by a mantling 30 which is able to resist pressure and which can be shut off against the outer water.
3. In a submarine boat, turbines, impelled by the exhaust gases of Diesel motors, and compressors, both coated with a cover which 35 is not able to resist pressure, but provided with an exhaust pipe which is provided with mantlings and stop cocks for putting the turbine out of operation whilst the Diesel motors remain operating without loading.
4. In a submarine boat, turbines, impelled by the exhaust gases of Diesel motors, and compressors, and provided with cooling devices to cool the turbine more promptly.
5. In a submarine boat, turbines, impelled by the exhaust gases of Diesel motors, and compressors, of which only the turbines are 40 45 50 arranged outboard.

In testimony whereof I have signed my name to this specification.

GEORG JOACHIM KARL BEHRMANN.
